WINDOW VALANCE

Arthur B. Hoffheimer and Sidney M. Kaufman,
Chicago, Ill.

Application May 3, 1933, Serial No. 669,118

7 Claims. (Cl. 156—13)

This invention relates to improvements in window valances, a term used in interior decorating to designate a narrow strip extending across the head of a window to conceal the upper end portions of the drapes and to otherwise add to the artistic effect. A valance necessarily harmonizes with the drapes or hangings and frequently is made of or covered by the same material as the drapes. Again, valances may be made in different styles, one of which is a decorative strip or panel of some stiff material mounted so that it stands away from the window frame, and provides the support for the drapes or other hangings. This style of valance is also made adjustable lengthwise so that it will fit windows of different widths, thus avoiding the necessity of having them made to the exact measurements of each window in the room. Perhaps the simplest form of adjustable valance is one made up of two or more telescoping sections or panels with the edges of one panel sliding in grooves on the back of another panel.

The improved construction for valance herein disclosed utilizes the idea of telescoping panels, but does so in a novel manner which overcomes certain objections to the more common styles of adjustable valances, the chief of which is the inability to use such decorative touches as ruffles and other forms of trimming along the edges. As a result the ornamentation of these valances has been confined to surface decoration and a consequent tendency toward garishness in an effort to counteract the unsightly appearance of the edges.

The novel features of the improved valance, therefore, permit of a more flexible treatment and, therefore, a greater adaptability in carrying out the desired decorative effects, all of which will be more apparent in connection with the description to follow and the accompanying drawings illustrating a preferred embodiment of the invention, wherein

Figure 1 is a perspective view of a window valance as it appears from the front;

Figure 2 is a view of the same valance in rear elevation with the panels retracted;

Figure 3 is a view similar to Figure 2, showing the panels fully extended;

Figure 4 is an enlarged detail view in vertical section taken on line 4—4 of Figure 2;

Figure 5 is an enlarged perspective view of one end portion of the central panel; and

Figure 6 is an enlarged perspective view of the inner end portion of one of the end panels.

As shown in Figure 1, the valance is mounted to extend across the top of a window and sup-

ports the side drapes 1 by means of a rod 2 concealed behind the valance. So far as the construction of the valance is visible, it appears to be made up of three sections, namely, a center panel 3 and two end panels 4, 4, the former being shorter and somewhat wider than the end panels, although all sections may be of equal width with only transverse lines to indicate the division between them.

The surfaces of the panels are preferably plain except for the color which may be the same as that of the drapes or harmonizing with it. The surface covering may be fabric, paper or other color coating, although surface ornamentation may be used if desired. Along the lower edges of the panels are lengths of trimming 5 in the form of a narrow strip of material or fabric plaited or ruffled and attached so as to conceal the lower edges of the panels. The material of the edge trimming may be a plain or figured fabric and whether it is of a contrasting or harmonizing color depends on the effect sought to be obtained. In any event it appreciably softens the line of the bottom edge of the valance and otherwise enhances the appearance of the ensemble.

As already indicated, the valance is made up of three sections or panels preferably made of a light composition board of ample thickness to afford a substantial construction. The inner portions of the end panels 4, 4 have overlapping and endwise sliding connection with the center panel 3, and at the outer end of each end panel is fixed a block 6 extending edgewise and rearwardly therefrom, said blocks being preferably rectangular pieces of wood, say, one (1) inch in thickness, having the same height as that of the panels and a width equal to distance the valance is to be spaced from the upper part of the window, say, four (4) or five (5) inches.

Extending across the back of the center panel 3 and along its upper edge is fastened a track member 7 having a flange 7^a along its lower edge and spaced from the surface of the panel to form a groove to receive the upper edges of the end panels and support them in sliding connection therewith.

The lower edges of the end panels, however, do not have sliding connection with the central panel by means of the simple telescoping groove and edge arrangement used at the upper edges, but rather by a flexibly mounted track member 8 engaged by the rails 9, 9 fastened to the back of the end panels. Thus as shown in Figure 5, the track member 9 is spaced away from the back of the central panel, being preferably an-

- chored at a point midway between its ends by 50 nails passing through the track member and the end of a transverse reinforcing cleat 10 extending between the upper and lower track members 5 and serving as a stop member to limit the inward sliding movement of the end panels as shown in Figure 2. The end portions of the track member 8 are secured to the panel by means of a pair of U-shaped metal strips 11, 11 fastened 10 at one end at or near the free ends of its track member, and at their other ends to the lower edge of the panel, the portion between their ends forming loops which clear the lower edges of the end panels as well as the trimming attached 15 thereto.
- On the back of each end panel is fastened a thin strip of wood 9 extending parallel with the lower edge and spaced therefrom a distance of an inch or so. These strips form rails or track 20 members and are preferably cut with rabbets along their bottom edges to provide narrow flanges 9^a lying against the surface of each panel and extending downwardly toward the bottom edges thereof.
- To assemble the sections of the valance, the 25 inner ends of the end panels are inserted endwise between the track members 7 and 8 of the center panel, their upper edges engaging grooves formed by the track member 8 and the rails 30 9, 9 bearing edgewise upon the flexibly mounted lower track member 7 through the medium of the interlocking flanges 7^a and 9^a, thereby holding the panels in their respective planes.
- By this arrangement, the lower edges of the 35 end panels slide freely against the back of the center panel and are not confined within grooves as in the case of the upper edges, and thus permits the trimming 5 to be applied along the lower edges of the end panels without interfering with the adjustability, or to put it a different way, it permits an adjustable valance to be trimmed along its lower edge, inasmuch as the panels 40 can be shifted with the trimming in place.
- Manifestly the upper edge of the valance might 45 also be treated in the same manner as the lower edge, if desired, in which case the same arrangement of track members and rails would be used at the top as well as at the bottom of the panel.
- In the mounting of the valance to the window 50 frame, ordinary screw eyes 12 are inserted in the inner faces of the end pieces 6, and these engage hooks screwed into the window frame. These end pieces also serve to support the ends of the rod 2 carrying the drapes, as already 55 mentioned in connection with Figure 1, and thus take the place of brackets fastened to the window trim such as are ordinarily used for this purpose. Thus by slotting the inner faces of the end pieces 6, upwardly opening recesses 6^a, 6^a are formed 60 to receive the ends of one or more rods spaced apart transversely of the space between the valance and the window trim.
- Having set forth a preferred embodiment of 65 our invention, we claim:
1. A valance for windows and the like, comprising a plurality of telescoping sections extensible lengthwise, said sections having contacting track members extending lengthwise thereof and spaced inwardly from one of their longitudinal 70 edges, and means for fastening one of said track members to its section to permit the adjacent edge portion of another section to pass freely beneath it.
2. A valance for windows and the like, comprising a plurality of telescoping sections extensible lengthwise, coacting track members extending lengthwise of the back surfaces of said sections and spaced inwardly from one of their longitudinal edges, one of said track members being spaced away from its section to permit the adjacent edge portion of another section to slide therebetween. 80
3. A valance for windows and the like, comprising a plurality of telescoping sections extensible lengthwise, one of said sections having a rail fastened on its back surface and extending lengthwise thereof and spaced inwardly from one of its longitudinal edges, a track member mounted on the other section in alignment with said rail and spaced from the surface thereof to permit the adjacent edge portion of the first mentioned section to slide freely between said track member and the surface of its section. 85
4. A valance for windows and the like, comprising a plurality of telescoping sections extensible lengthwise, one of said sections having a rail fastened on its back surface and extending lengthwise thereof and spaced inwardly from one of its longitudinal edges, and a track member mounted on the back of the other section and spaced from the surface thereof, said rail and track member being adapted to have edge to edge sliding contact, thereby permitting the free overlapping sliding contact of adjacent marginal portions of said sections. 90
5. A valance for windows and the like, comprising a plurality of telescoping sections extensible lengthwise, one of said sections having a rail fastened on its back surface and extending lengthwise thereof and spaced inwardly from one of its longitudinal edges, a track member mounted on the back of the other section and means for securing said track member in spaced relation to its section, including U-shaped strips forming loops adapted to clear the adjacent edge of said first mentioned section. 100
6. An adjustable valance for windows and the like, comprising a plurality of panels having endwise sliding connection, a rail attached to the back of one of said panels and extending lengthwise thereof adjacent one of its longitudinal edges, a track member mounted on the back of the other panel in alignment with said rail, and U-shaped track supporting members connecting the ends of the track member with the adjacent edge of its panel and clearing the corresponding edge of the first mentioned panel. 110
7. An adjustable valance for windows and the like, comprising a central panel and two end panels adapted for endwise sliding connection with said central panel, a rail secured flatwise to the back of each of said end panels and extending lengthwise thereof adjacent one of their longitudinal edges, a track member mounted on the back of said central panel and having edgewise sliding contact with said rail, and metal U-shaped strips connecting the ends of said track member with the adjacent edges of its section and adapted to support said track member in spaced relation to its section and to clear the adjacent edges of the end panels. 120
